UNITED STATES PATENT OFFICE

HENRY V. NYE, OF WEST ALLIS, WISCONSIN, ASSIGNOR TO ALLIS-CHALMERS MANUFACTURING COMPANY, OF MILWAUKEE, WISCONSIN, A CORPORATION OF DELAWARE

CIRCUIT BREAKER CONTROL SYSTEM

Application filed June 30, 1928. Serial No. 266,612.

This invention relates to control systems for circuit breakers and the like.

One of the objects of the invention is to provide a control system in which the circuit breaker will be automatically reclosed after being tripped and if the circuit breaker does not remain closed after a predetermined number of reclosures it will remain open until the condition of the control system is readjusted.

Another object is the provision of a circuit breaker control system in which a motor driven controller is utilized and in which springs and the like are unnecessary for returning the controller to an initial position; more specifically, such a system in which the controller is always driven in the same direction.

A further object is the provision of a circuit breaker control system which is simple, reliable, and of minimum expense. Other objects will appear hereinafter as the description of the invention proceeds.

The novel features of the invention will appear from the specification and the accompanying drawing forming a part thereof and disclosing one embodiment of the invention, and all these novel features are intended to be pointed out in the claims.

The single figure of the drawing is a diagrammatic showing of one embodiment of the invention.

Referring to the drawing the circuit breaker 1 which is to be controlled is shown as adapted to open and close a circuit leading from a generator 2. This circuit is provided with an overload relay 3 which when energized closes the circuit to a trip coil 4. The trip coil 4 when energized is adapted to cause the opening of the circuit breaker 1 in any suitable manner as, for example, by releasing a latch which holds the circuit breaker closed as in the illustrated embodiment. The circuit breaker 1 may be operated to closed position by means here shown as a solenoid 5. It is clear that the circuit breaker and immediate operating means therefor may be of any suitable form. The circuit breaker is shown as provided with auxiliary contacts 6, 7 both of which are

arranged to make contact with their respective stationary contacts when the circuit breaker 1 is closed.

A relay 8 may be provided for controlling the circuit of the closing solenoid 5. Another relay 9 is provided for controlling a motor 10 for operating a controller 11. The relay 9 is provided with a holding contact 9^a and a control contact 9^b which latter initiates the controlling operation of the motor 10.

The controller 11 is preferably of the drum type and is diagrammatically indicated as driven in a suitable manner by the motor 10. The controller 11 has its surface 15 developed in the plane of the paper. Mounted on the surface of the controller are a number of contacts adapted to engage a number of relatively stationary contacts respectively, as will be more particularly set forth. A contact 12 which extends as here shown nearly around the circumference of the controller is adapted to bridge the stationary contacts 13, 14 after the controller has moved slightly to the left as viewed in the drawing. Another contact 15 is provided which, in the position of the controller as shown, bridges two stationary contacts 16, 17. The length and relation of the contacts 12 and 15 is such that the contact 12 bridges the contacts 13, 14 before the contact 15 leaves the contacts 16, 17. The controller is further provided with a plurality of contacts 18, 19, 20, the number of which is a matter of choice, and each of these contacts is adapted to bridge the stationary contacts 21, 22 in succession as the controller is rotated. The controller is provided with still another contact 23 adapted to bridge the stationary contacts 24, 25. The contact 23 is so disposed that before contact 12 leaves contacts 13, 14 the contact 23 will have engaged contacts 24, 25. The purpose of the various contacts hereinbefore noted will be clear from the operation of the system, as will be set forth.

The various control circuits may be supplied with current from a source here shown as an independent generator 26, though of course any suitable source may be utilized. 100

The source 26 is connected to the control buses 27, 28.

The system also includes, as here shown, a control switch 29 normally making contact with contacts 30 and also adapted to bridge contacts 31. Another control switch 32 is provided adapted when energized to close the circuit to the relay 8.

The connections of the apparatus will be best understood by a description of the operation of the system which is as follows. Assuming the parts to be in the position as shown on the drawing and that an overload or other abnormal condition occurs in the circuit controlled by the circuit breaker 1, the relay 3 will energize the trip coil 4, the circuit being from control bus 27 through relay contacts 3, trip coil 4, auxiliary switch 7 to control bus 28. Simultaneously therewith the relay 3 energizes the relay 9, the circuit being through contacts 30 of switch 29 and the relay contacts 3, as is clear. The opening of circuit breaker 1 as a result of energization of the trip coil 4 also opens the auxiliary switches 6 and 7 and deenergizes relay 3. The relay 9 however remains in the energized position a circuit through its operating coil having been closed from bus 28 through contact 9^a through contacts 17, 15, 16 to the bus 27.

The energization of relay 9 also causes the starting of the motor 10 by closure of a circuit from bus 28 through motor 10, contacts 9^b to bus 27. Rotation of motor 10 causes contact 12 to bridge contacts 13, 14 thereby completing an independent circuit between buses 27, 28 through motor 10. The motor 10 is now in a condition to continue its rotation independently of the position of relay 9. As soon as contact 15 leaves contacts 16, 17 the relay 9 is deenergized.

When contact 18 of the controller reaches and bridges contacts 21, 22 a circuit is completed between buses 27, 28 through relay 8 the closure of which energizes the closing solenoid 5 from the control buses, as is clear. The solenoid 5 consequently closes the circuit breaker 1. It will be remembered that the motor 10 keeps on rotating, being still energized through contact 12. Consequently, if the circuit breaker 1 is again opened, the abnormal condition still obtaining on the main line, it will be again closed when contact 19 bridges contacts 21, 22, in a manner similar to that described in connection with contact 18. It will be clear that the circuit breaker 1 will be reclosed, if it does not remain closed, a predetermined number of times depending upon the number of contacts 18, 19, 20.

If the circuit breaker 1 is again tripped out after the last contact such as 20 has caused it to close, the controller 11 will be driven by motor 10 until contact 12 leaves contacts 13, 14 thus stopping motor 10. The

circuit breaker 1 will now remain open until the system is readjusted for automatic reclosure of the circuit breaker. This may be accomplished by closure of control switch 32 thereby causing relay 8 to energize solenoid 5 to close circuit breaker 1. The closure of the circuit breaker also closes auxiliary contact 6 thereby completing a circuit through motor 10 through that auxiliary contact and through the controller contacts 25, 28, 24. The motor 10 now runs until the contact 23 leaves contacts 24, 25 thereby stopping the motor and the controller in the position as shown on the drawing in which position it is again in condition to cause automatic reclosure of the circuit breaker 1 in response to the abnormal condition relay 8.

If it be assumed that the circuit breaker 1 opens in response to an abnormal condition, with the parts as shown in the drawing, and that after contact 18 has caused reclosure of the circuit breaker 1 it remains closed, the motor 10 will as hereinbefore described, continue to rotate and each succeeding contact 19, 20, etc. will cause energization of the closing solenoid 5, but this will not change the condition of the circuit breaker as it has been assumed that the abnormal condition was removed before the first reclosure. Under these conditions the motor 10 will not stop when contact 12 leaves contacts 13, 14, but will continue to rotate because there is a circuit through the motor from bus 28 through auxiliary contact 6 and controller contact 23 to bus 27. It will therefore be evident that the controller 11 will be brought to its initial position by motor 10 if the circuit breaker 1 does not trip out after the last contact such as 20 has caused the closure thereof. If such is not the case then a controller stops short of its initial position and no further automatic reclosures of the circuit breaker 1 can take place, until the system is readjusted as hereinbefore described.

The circuit breaker 1 may be tripped manually by operation of the control switch 29 to bridge contacts 31 thereby energizing trip coil 4. Such manual tripping does not however energize relay 9 as the control switch 29 also leaves contacts 30 thereby opening the possible circuit to relay 9.

It should be understood that it is not desired to limit the invention to the exact details of construction shown and described, for obvious modifications within the scope of the claims may occur to persons skilled in the art.

It is claimed and desired to secure by Letters Patent:

1. In combination, a circuit breaker, means for closing said circuit breaker, means including an overload relay for causing said circuit breaker to open, a rotary

- timing device having an initial position, a single motive device for rotating said timing device in one direction only, means responsive to the actuation of said overload 5 relay for energizing said motor and thereby causing said timing device to rotate from its initial position continuously through one complete revolution, and means for causing said timing device to actuate said circuit breaker closing means to reclose said circuit breaker. 10
2. A circuit breaker reclosing system comprising an automatic circuit breaker, means for closing said circuit breaker, means for causing said circuit breaker to open, a controller having an initial position, a single motive device for operating said controller from its initial position through its intermediate position to its initial position in one direction only, means whereby automatic opening of said circuit breaker initiates the operation of said single motive means, and means including a plurality of spaced contacts on said controller for repeatedly causing said closing means to close said circuit breaker a predetermined number of times only. 15
3. In a circuit breaker reclosing system comprising an automatic circuit breaker, means for closing said circuit breaker, means for causing said circuit breaker to open, a controller having an initial position, a single motor device for rotating said controller, means operable upon opening of said circuit breaker for causing said motor device to continually rotate said controller in one direction only from said initial position through one complete revolution, and means including a contact on said controller for causing said closing means to reclose said circuit breaker. 20
4. In combination, an automatic circuit breaker, means for closing said circuit breaker, means for causing said circuit breaker to open, a controller having an initial position, a motor for operating said controller from its initial position through its intermediate positions to its initial position by movement of said motor in the same direction, means whereby automatic opening of said circuit breaker causes said motor to operate, means including a contact on said controller for causing said closing means to close said circuit breaker, and means dependent upon said circuit breaker remaining closed for causing said motor to bring said controller to its initial position. 25
5. In combination, an automatic circuit breaker, means for closing said circuit breaker, means for causing said circuit breaker to open, a controller having an initial position, a motor for operating said controller from its initial position through its intermediate positions to its initial position by movement of said motor in the same direction, means whereby automatic opening of said circuit breaker causes said motor to operate, means including a contact on said controller for causing said closing means to close said circuit breaker, and means dependent upon said circuit breaker remaining closed for causing said motor to bring said controller to its initial position. 30
6. In combination, an automatic circuit breaker, means for closing said circuit breaker, means for causing said circuit breaker to open, means including a contact on said controller for causing said closing means to close said circuit breaker, and means dependent upon said circuit breaker remaining open for causing said motor to stop before said controller has reached its initial position. 35
7. In combination, an automatic circuit breaker, means for closing said circuit breaker, means for causing said circuit breaker to open, means including motor rotating always in the same direction when in operation for controlling said circuit breaker to automatically reclose a predetermined number of times, means whereby after a predetermined number of reclosures said circuit breaker remains open if again opened, and manually controllable means for causing closure of said circuit breaker and for resetting said reclosing control means in condition to again automatically reclose said circuit breaker when opened. 40
8. In combination, an automatic circuit breaker, means for closing said circuit breaker, means for causing said circuit breaker to open, a controller, a motor operable always in the same direction for operating said controller, means whereby automatic opening of said circuit breaker causes said motor operated controller to cause reclosure of said circuit breaker a predetermined number of times, means whereby after a predetermined number of reclosures said circuit breaker remains open if again opened, and manually controllable means for causing said motor to restart in the same direction to bring said controller to a position in which further movement thereof will again be adapted to automatically cause a predetermined number of reclosures of said circuit breaker. 45
9. In combination, a circuit breaker, means for closing said circuit breaker, means for causing said circuit breaker to open, a controller for controlling the reclosure of said circuit breaker, a motor for operating said controller, a contact on said controller for maintaining the circuit of said motor closed for a predetermined extent of travel of said controller, an auxiliary contact on said circuit breaker closed when said circuit breaker is closed, a second contact on said controller connectible in series with said auxiliary contact, and means whereby joint closure of said second and auxiliary contacts maintains the same circuit through said motor after said first controller contact has been opened. 50
10. In combination, a circuit breaker, means for closing said circuit breaker, means for causing said circuit breaker to open, a controller, a motor for operating said controller, means including a relay re- 55

sponsive to said opening means for closing a circuit for said motor, means including a contact on said controller for maintaining the circuit of said relay for a predetermined extent of travel of said controller, means including a second contact on said controller operative to maintain the circuit through said motor before said first contact has opened the maintaining circuit of said relay, and means including another contact on said controller for causing said closing means to close said circuit breaker.

10. In combination, a circuit breaker, means for closing said circuit breaker, means for causing said circuit breaker to open, a controller, a motor for operating said controller, means including a relay responsive to said opening means for closing a circuit for said motor, means including a contact on said controller for maintaining the circuit of said relay for a predetermined extent of travel of said controller, means including a second contact on said controller operative to maintain the circuit through said motor before said first contact has opened the maintaining circuit of said relay, an auxiliary contact on said circuit breaker closed when said circuit breaker is closed, means including a third contact on said controller whereby joint closure of said third contact and said auxiliary contact maintains a circuit through said motor after said second controller contact has opened, and means including another contact on said controller for causing said closing means to close said circuit breaker.

11. In combination, a circuit breaker, means for closing said circuit breaker, means operable when energized to cause said circuit breaker to open, a rotatable controller having a plurality of spaced contacts thereon, a motor for rotating said controller, a relay, overload responsive means for causing said relay to simultaneously energize said circuit breaker opening means and said motor, means for maintaining the energization of said motor through certain of said contacts until said controller has rotated continuously in one direction through one complete revolution, and means for periodically energizing said circuit breaker closing means through other of said contacts during the rotation of said controller.

12. In combination, an automatic circuit breaker, means for closing said circuit breaker, means for causing said circuit breaker to open, a controller, a single motor for operating said controller continuously through one complete revolution always in the same direction when the circuit thereof is closed, means whereby automatic opening of said circuit breaker causes closure of said motor circuit, and means including a plurality of spaced contacts on said controller for repeatedly causing said closing means to

close said circuit breaker until it remains closed.

13. In combination, an automatic circuit breaker, means for closing said circuit breaker, means for causing said circuit breaker to open, a controller, a motor for operating said controller, said motor rotating always in the same direction when the circuit thereof is closed, means whereby automatic opening of said circuit breaker causes closure of said motor circuit, means including a contact on said controller for causing said closing means to close said circuit breaker, and means dependent on said circuit breaker remaining closed for causing said motor to bring said controller to its initial position.

14. In combination, an automatic circuit breaker, means for closing said circuit breaker, means for causing said circuit breaker to open, a controller, a motor for operating said controller, said motor rotating always in the same direction when the circuit thereof is closed, means whereby automatic opening of said circuit breaker causes closure of said motor circuit, means including a contact on said controller for causing said closing means to close said circuit breaker, and means dependent on said circuit breaker remaining open for causing said motor to stop before said controller has reached its initial position.

15. In combination, a circuit breaker, means for closing said circuit breaker, means for causing said circuit breaker to open, a controller for controlling the reclosure of said circuit breaker, a motor for operating said controller, said motor rotating always in the same direction when the circuit thereof is closed, a contact on said controller for maintaining the circuit of said motor closed for a predetermined extent of travel of said controller, an auxiliary contact on said circuit breaker closed when said circuit breaker is closed, a second contact on said controller connectible in series with said auxiliary contact, and means whereby joint closure of said second and auxiliary contacts maintains the same circuit through said motor after said first controller contact has been opened.

16. In combination, a circuit breaker, means for closing said circuit breaker, means for causing said circuit breaker to open, a controller, a motor for operating said controller, said motor rotating always in the same direction when the circuit thereof is closed, means including a relay responsive to said opening means for closing a circuit for said motor, means including a contact on said controller for maintaining the circuit of said relay for a predetermined extent of travel of said controller, means including a second contact on said controller operative to maintain the

circuit through said motor before said first contact has opened the maintaining circuit of said relay, and means including another contact on said controller for causing said closing means to close said circuit breaker.

17. In combination, a circuit breaker, means for closing said circuit breaker, means for causing said circuit breaker to open, a controller, a motor for operating said controller, said motor rotating always in the same direction when the circuit thereof is closed, means including a relay responsive to said opening means for closing a circuit for said motor, means including a contact on said controller for maintaining the circuit of said relay for a predetermined extent of travel of said controller, means including a second contact on said controller operative to maintain the circuit through said motor before said first contact has opened the maintaining circuit of said relay, an auxiliary contact on said circuit breaker closed when said circuit breaker is closed, means including a third contact on said controller whereby joint closure of said third contact and said auxiliary contact maintains a circuit through said motor after said second controller contact has opened, and means including another contact on said controller for causing said closing means to close said circuit breaker.

18. In combination, an automatic circuit breaker, means for closing said circuit breaker, means for causing said circuit breaker to open, a drum controller, a motor for operating said controller, means whereby automatic opening of said circuit breaker causes said motor to operate, means including a predetermined number of contacts on said drum for causing repeated energization of said closing means, and means including a contact on said drum in circuit with said motor whereby said motor is maintained in operation irrespective of the condition of said circuit breaker until said drum has made nearly one complete revolution.

19. In combination, an automatic circuit breaker, means for closing said circuit breaker, means for causing said circuit breaker to open, a drum controller, a motor for operating said controller, means whereby automatic opening of said circuit breaker causes said motor to operate, means including a predetermined number of contacts on said drum for causing repeated energization of said closing means, and means including a contact on said drum in circuit with said motor whereby said motor is maintained in operation irrespective of the condition of said circuit breaker until said drum has made nearly one complete revolution, and means dependent upon the condition of said circuit breaker for causing

said motor to rotate said drum the remainder of said one revolution.

20. In combination, a circuit breaker, means for closing said circuit breaker, means for causing said circuit breaker to open, a drum controller, a motor for operating said controller, means whereby automatic opening of said circuit breaker causes said motor to operate, a contact on said drum extending peripherally nearly 360° , means including relatively stationary contacts for completing a circuit through said motor through said contact, a second contact on said drum insulated from said first named contact, said second contact extending peripherally nearly the difference between 360° and the extent of said first contact, means including relatively stationary contacts for completing the circuit of said motor through said second contact, and means including a predetermined number of contacts on said drum for causing energization of said closing means.

In testimony whereof, the signature of the inventor is affixed hereto.
